Inventor

UNITED STATES PATENT OFFICE.

WILLIAM WALLACE McLAURIN, OF BROOKFIELD, MASSACHUSETTS.

CLOTHING-PATCH.

1,113,030.

Specification of Letters Patent.

Patented Oct. 6, 1914.

Application filed January 7, 1913. Serial No. 740,648.

To all whom it may concern:

Be it known that I, WILLIAM WALLACE McLAURIN, a subject of the King of England, residing at Brookfield, in the county of 5 Worcester and State of Massachusetts, have invented certain new and useful Improvements in Clothing-Patches; and I do hereby declare the following to be a full, clear, and exact description of the invention, such as 10 will enable others skilled in the art to which it appertains to make and use the same.

This invention relates to wearing apparel and more particularly to the provision of means for patching or repairing rents in 15 stockings or the like.

An object of this invention is to eliminate the necessity of darning to fill a hole or tear by removing portions of the garment to include all irregular tears or slits and inserting a regular shaped piece of fabric in place 20 of the removed portions.

A further object is to provide a temporary foundation for the insertible piece and an extending area to receive and fasten to the 25 portions of the garment surrounding the opening.

A further object of this invention is to provide an insertible section which is mounted upon a temporary backing, which may 30 subsequently be removed. This insertible piece is stitched to the adjacent portions of a garment before the backing is removed, which backing has extensions from the edges of the insertible portion for temporary adhesion to the adjacent portions of a garment.

Further objects will be apparent from the following specification, appended claims and drawings, in which,

40 Figure 1 is a perspective view of one of the insertible members, Fig. 2 shows a piece of fabric ready to receive the insertible member, Fig. 3 shows a conventional die to cut a uniform opening through the fabric, Fig. 4 is a sectional view showing the insertible member applied, and Fig. 5 is a view of the completed operation.

In the event of a garment such as stockings and the like becoming worn or torn, it 50 is easier to insert a piece of similar fabric and to stitch the edges together than to build up a ply of fabric as by the darning process. Also, when the tear is irregular, it is somewhat difficult to fit the inserted piece, so, to meet any requirement, the insertible pieces may be made and sold on the market in

various sizes and fabrics together with dies of a size uniform to the insertible pieces. Then to repair a garment, a uniform opening is formed in the garment to include the 6 irregularities of the tear in which the insertible piece is placed.

In order to hold the insertible piece and the object to be repaired in proper relation to each other preparatory to sewing, a paper 65 or other backing is secured to the insertible piece and the adjacent portions of the garment. After the two pieces are stitched together, the backing is removed.

In the drawings, 10 indicates a garment 70 having an opening 11 formed therein as by a die 12. It is not necessary that any particular shape be adopted but it is necessary that the adopted shape should correspond to insertible pieces 13 so that a perfect fit is possible with each repair. I have shown a circular insertible portion and a correspondingly circular die for forming a circular opening. These dies and insertible pieces 75 may be made in various sizes to repair any 80 tear and are made of uniform outlines to facilitate the fitting of the insertible piece in the opening. A piece of gummed paper or similar substance 14 of a larger area is secured to each of said insertible pieces so 85 that an exposed portion extends about the insertible piece, which exposed portion is moistened and secured to the adjacent portions of the garment about the opening 11. Then by any desired form of stitching 15 90 the two edges are fastened together after which the paper or other backing may be removed. The adhesive on the backing of the insertible pieces must be soluble so that it may be readily applied and removed. Also 95 the backing is a necessity to procure a proper repair as the patch and adjacent portions of the garment are held taut during the step of sewing the patch in place.

Having thus described my invention, I 100 claim:

1. In an article of the class described, a piece of fabric intended for insertion in an opening in a garment a gummed backing for said piece of fabric, said backing having 105 a greater area than the piece of fabric to expose a portion of the gummed surface, said exposed gummed surface being intended to adhere to a garment about an opening, and said backing being removable after the 110 piece of fabric is stitched in the garment.

2. In an article of manufacture, a patch

to be applied to an article to be repaired, a backing and support for said patch, said backing having greater dimensions than the patch, said backing having one face thereof 5 gummed to retain said patch thereon temporarily, the gummed backing for said supporting member having the extended gummed face thereof adapted to be secured to an article to be repaired, the gummed face 10 of said backing being applied by moistening,

said patch being intended to be stitched to the article to be repaired, and said backing being intended to be removed after said patch has been secured by stitching.

In testimony whereof I affix my signature 15 in presence of two witnesses.

WILLIAM WALLACE MCLAURIN,
